TRIMMER FOR WALL PAPER OR THE LIKE

Frank A. Armon, 718 Plymouth Ave. N., Rochester, N.Y.

Filed July 31, 1961, Ser. No. 66,120

Term of patent 14 years

(Cl. D22—3)

FIG.1

FIG.3

FIG. 1 is a right side elevational view of a trimmer for wall paper or the like, showing my new design;

FIG. 2 is a front edge view of the same;

FIG. 3 is a left side elevational view of the same; and FIG. 4 is a fragmentary top plan view of the same on a larger scale, with parts broken away.

I claim:

The ornamental design for a trimmer for wall paper or the like, substantially as shown.
